FIG. 1

FIG. 2

FIG. 3

FIG. 4

INVENTOR
R. B. SHERMAN
By Hazard and Miller
ATTORNEYS

UNITED STATES PATENT OFFICE.

ROGER B. SHERMAN, OF LOS ANGELES, CALIFORNIA.

CERAMIC.

Application filed June 29, 1927. Serial No. 202,241.

My invention relates to ceramics and, while of general application, is especially intended for surface ornamentation of vases, jars, and the like.

5 It is an object of this invention to provide a simple and efficient method whereby beautiful effects may be produced on the surfaces of vases and jars by the use of colored tiles which are assembled in a manner of mosaics on the surface thereof.

10 My invention consists in the steps of the method and the resulting product hereinafter described and claimed.

15 Referring to the drawings which form a part of the specification:

Figure 1 is a front elevation of a vase to which my invention is applied.

20 Figure 2 is a vertical cross section thereof on the lines 2—2 of Fig. 1.

Figure 3 is a front elevation of a vase with parts broken away, showing a modified form of my invention.

25 Figure 4 is a perspective view of a tile, on an enlarged scale.

Figure 5 is an edge view of a tile, on an enlarged scale.

30 In the drawings 1 designates a vase of any desired or preferred construction. The same may be of any plastic material used in making vases and the same may be either sun dried or burnt, although usually burnt and unglazed vases are preferred.

35 Suppose that the vase is to receive a surface ornamentation of a geometrical pattern around the central zone 2, as shown in Fig. 1, zone 2 is formed by using small rectangular shaped glazed tiles 3 of different colors to make the pattern, as will be understood.

40 The tile 3 consists of a body portion 3' and a glazed surface 3''. The tiles are preferably very thin. A plastic composition of clay 4 is applied on the reverse side of the tile by any convenient means, such as a trowel, and the same is then stuck on the vase in its proper place and thus the pattern is built up. It should be noted here that the size of the tiles is immaterial since they extend in either direction of the middle of the vase.

45 The built up pattern 2 will form upper and lower shoulders 5 and 6 with the body of the vase 1. These shoulders are filled in with a plastic composition, gradually tapering to a feather edge with the jar 1, as shown at 7 and 8. The jar may now be burnt again or

sun dried, as desired, and it may also be dyed or colored in any manner to give it an antique appearance.

50 In Fig. 3 I have shown a modified form of the invention in which a vase 9 is provided with a recessed zone 10, the depth of the recess 10 corresponding to the thickness of the tiles 3. The tiles are applied in this pattern in the same manner as described in connection with the vase 1. Since the thickness of the tiles is the same as the depth of the recess 10, the outer face of the pattern will be flush with the adjacent face of the vase 9 and it is unnecessary to eliminate any shoulders formed by the projecting tiles. However, the disadvantage of the method shown in connection with Fig. 3 is that the tiles must be of a size to exactly fit the width of the zone 10.

55 It will be obvious that any mosaic pattern may be formed on the surface of ceramics by my method and the multi-colored tiles may 70 be of any shape or a combination of them, using variously shaped and colored tiles in forming the pattern.

60 Various changes may be made by those skilled in the art without departing from the 80 spirit of my invention as claimed.

I claim:

1. A method of surface ornamentation for ceramics comprising cementing tiles in the form of a design to the outer surface of a 85 ceramic, and applying a plastic composition on the ceramic adjacent the design to make the same flush with the body of the ceramic.

2. A method of surface ornamentation for ceramics comprising cementing multi-colored 90 tiles in the form of a design to the outer surface of a ceramic, said cementing including the application of a plastic composition between the body of the ceramic and the tiles.

3. A method of surface ornamentation for 95 ceramics comprising cementing multi-colored glazed tiles in the form of a design to the outer surface of a ceramic, and making the body of the ceramic flush with the outer edges of the design.

4. A ceramic provided with a surface ornamentation in the form of a design made by cementing colored tiles to the surface thereof, the body of the ceramic adjacent said design being flush therewith.

100 In testimony whereof I have signed my name to this specification.

ROGER B. SHERMAN.
